Attorney

UNITED STATES PATENT OFFICE

ORLANDO B. HUBER, OF MILWAUKEE, WISCONSIN

VALVE

Application filed December 29, 1930. Serial No. 505,324.

This invention relates to plumbing fixtures and more particularly to valves and actuating means therefor.

Numerous types of valves have been incorporated in plumbing fixtures and varying measures of successful operation have been attained. Most types have functioned satisfactorily for a short time and then become leaky and ineffective due to wear, misalignment, for faulty functioning of the actuating mechanism.

One object of the present invention is to overcome the above mentioned defects by providing a hollow expansible valve which will retain its effectiveness for an indefinite period of time.

Another object is the provision in a plumbing fixture of a flexible connection between the valve and its actuating mechanism.

20 A further object is to simplify and improve the construction of devices of this character by materially reducing their cost and increasing their life and effectiveness.

Other objects and advantages will appear 25 from the following description of an illustrative embodiment of the present invention.

In the drawing:

Figure 1 is a vertical sectional view through a plumbing fixture showing a valve 30 constructed in accordance with the teachings of the present invention together with actuating means therefor.

Figure 2 is a sectional view taken on the line 2—2 of Figure 1.

35 Figure 3 is a vertical sectional view through the valve and actuating means taken at right angles to the showing in Figure 1.

Figure 4 is a view similar to Figure 3 showing a modified form of the valve.

40 The plumbing fixture selected for illustrating the valve and actuating means therefor comprises an overflow pipe 10 provided at its lower extremity with a usual T-fitting 11. An elbow 12 is retained on the upper 45 extremity of the pipe 10 in the usual manner and registers with an overflow opening in the wall 13 of the tub. The elbow 12 is provided with a usual flange portion 14 adapted to surround the overflow opening and bear against the wall of the tub. A ring 15 is adapted to be

passed through the overflow opening of the tub and engage an internally threaded portion of the elbow 12. A flange 16 formed on the ring serves to engage the inner wall of the tub to retain the elbow in desired position and also serves as a means to which an escutcheon 17 may be secured by means of screws 18. The escutcheon is provided with the usual water drainage openings 19. The escutcheon is provided with a usual centrally disposed vertical slot 20 through which a valve actuating lever 21 may be inserted and manipulated in a manner to be hereinafter more specifically described.

The T-fitting 11 is provided with a longitudinal bore which forms a valve chamber 22. This chamber 22 is in open communication with the lower extremity of the fitting which is adapted to receive the discharge or soil pipe (not shown). The horizontal arm 70 of the fitting 11 is threaded in the usual manner to receive the drain pipe (not shown) which leads from the waste opening of the tub. A passage 23 in the horizontal arm of the fitting leads to the valve chamber 22 and communication between the drain pipe and soil pipe is controlled by a valve 24.

The valve 24 comprises a hollow cylindrical member 25 longitudinally split to make it expansible to effect a sealing contact with the wall of the valve chamber 22. A coil spring 26 is transversely disposed within the hollow cylindrical valve 24 to normally tend to spread the member 25 to insure sealing contact with the wall of the valve chamber. This coil spring 26 is fastened to the inner wall of the valve 24 in any approved manner. In Figure 3 of the drawing the connection is effected by the use of solder. A modified form of spring mounting is shown in Figure 4 and will hereinafter be more specifically described. The coil spring 26 serves a dual purpose of maintaining the expansible valve in contact with the wall of the chamber and also to provide a flexible means upon which the valve actuating mechanism may be mounted.

The valve actuating mechanism comprises a fitting 27 provided with a bore 28 for receiving the spring 26 prior to its application 100

to the valve 24. An extended portion 29 of the fitting is provided with a screw threaded bore 30 adapted to receive the threaded end of a connector link 31. A suitable lock nut, 5 carried on the link 31, serves to effect a locking connection when the parts have been adjusted to the desired position. The upper end of the link 31 is pivotally mounted upon a pin 32 carried on the inner end of the actuating lever 21. The lever 21 is rockably mounted on a pin 33 which is positioned in the ears 34 on the escutcheon 17. A suitable operating handle 35 is retained on the outer extremity of the lever 21.

15. A brief description of the operation of the valve actuating means will serve to illustrate the simplicity and the positive operation of the valve. As the handle 35 is drawn downwardly, the lever 21 is rocked upon the pin 20 33 and the valve 24 is raised through the action of the link 31 and the fitting 27 which is mounted upon the coil spring 26. As the valve 24 is raised communication between the drain pipe of the tub and the discharge or 25 soil pipe is established to thereby drain the water from the tub. The valve may be closed merely by raising the handle 35 until the lower extremity of the valve 24 contacts with the inwardly directed flange 36 which is formed 30 at the lower end of the valve chamber 22.

It will be noted at this time that the construction of the valve is such that a virtually unimpeded passage is provided for the free passage of water from the overflow pipe 35 to the discharge pipe at all times by reason of the hollow formation of the valve 24. It will also be noted that the entire valve and 40 actuating mechanism may readily be withdrawn from the fixture through the overflow pipe 10 merely by removing the escutcheon 17.

The valve 24' shown in Figure 4 of the drawing is similar in many respects to that illustrated in Figs. 2 and 3 and comprises a member 25', a coil spring 26', a fitting 27', a bore 28' for receiving the coil spring 26', an extended portion 29' on the fitting and a link 31' adjustably connected to the valve in the manner previously described. The modification in construction lies in the mounting means for the spring 26'. In the present instance the member 25' is provided with threaded holes 37 adapted to receive studs 37' which extend into the ends of the coil spring 26'. Collars 38 are positioned upon the inner 50 wall of the member 25' in such a manner that their inwardly directed flanges 39 actually enter into enlarged ends 40 formed at the ends of the bore 28'. By reason of this construction it is possible to build up small valve mechanisms embodying all of the advantages of the other form without sacrificing strength and durability. In such cases the spring elements 26' would be so small that they could not long withstand the strain of repeated operation without losing their effectiveness by 60

reason of their becoming misshapen. In the construction illustrated in Figure 4 it will be apparent that virtually no strain is placed upon the spring 26'. The flanges 39 contact with the ends 40 of the fitting surrounding the bore 28' to take the strain of valve motion. 70

It will readily be seen from the foregoing that a simple, inexpensive, and effective valve has been provided which will overcome the difficulties common in present types of plumbing fixtures. While the valve shown and described is designed primarily for operation by longitudinal displacement, it is quite obvious that a rotatable valve might well be substituted therefor. A port in the valve member could be provided so that the functioning of the rotatable valve would be identical with that previously described in detail. 80

While the device has been described in considerable detail, various changes may be made in its embodiment without departing from or sacrificing the advantages of the invention as defined in the appended claims. 90

I claim:—

1. The combination of a cylindrical valve chamber having a port in the wall thereof, a hollow expansible valve in sealing contact with the wall of said chamber for controlling said port, a transversely disposed coil spring fixed in said valve, and an operating stem flexibly connected to said valve through said spring. 95

2. The combination of a cylindrical valve chamber having a port in the wall thereof, a hollow cylindrical valve within said chamber for controlling said port, said valve being longitudinally split to permit expansion thereof into sealing contact with the walls of said chamber, a coil spring fixed in said valve and extending across the same, and an operating stem mounted on said spring and flexibly connected to said valve through said spring. 100

3. The combination of a cylindrical valve chamber having a port in the wall thereof, a hollow expansible valve in sealing contact with the wall of said chamber for controlling said port, a transversely disposed coil spring fixed in the said valve, a valve actuating member operatively connected to said coil spring, and means carried by said valve to limit the flexible connection between said actuating member and said valve. 115

4. The combination of a cylindrical chamber and a port in the wall thereof, a hollow cylindrical valve within said chamber for controlling said port, said valve being longitudinally split, a transversely disposed coil spring positioned in said valve, said spring normally tending to spread said valve into sealing contact with the walls of said chamber, an actuating member flexibly connected to said valve through said spring, and means 120

carried by said valve for limiting the flexibility between said actuating member and said valve.

5. The combination of a cylindrical valve chamber having a port in the wall thereof, an expansible valve in said chamber, a spring in said valve for maintaining a sealing contact between said valve and the wall of said chamber, and valve actuating mechanism 10 flexibly connected to said valve through said spring.

In witness whereof, I hereunto subscribe my name this 13th day of December, 1930.

ORLANDO B. HUBER.
